Primary Examiner—Janice E Seeger(74) *Attorney, Agent, or Firm*—Hanley, Flight & Zimmerman, LLC**CLAIM**

The ornamental design for exposed legs for a play yard, as shown and described.

DESCRIPTION

FIG. 1 is a perspective view of exposed legs for a play yard.

FIG. 2 is a front view of the design of FIG. 1.

FIG. 3 is a rear view of the design of FIG. 1.

FIG. 4 is a right side view of the design of FIG. 1.

FIG. 5 is a left side view of the design of FIG. 1.

FIG. 6 is a top view of the design of FIG. 1; and,

FIG. 7 is a bottom view of the design of FIG. 1.

There is no fabric covering the exposed legs shown in any of FIGS. 1–7.

The features shown in broken lines are for illustrative purposes only and do not form part of the claimed design.
